TOY GUN INTENDED TO SIMULATE THE EJECTION OF SPENT CASES AT EACH FIRING OF AN EXPLOSIVE CAP
Giampiero Ferri, Via Stoppani 38, and Jori Marinai, Via Stoppani 29, both of Florence, Italy
Filed Aug. 12, 1965, Ser. No. 479,157
Claims priority, application Italy, Aug. 21, 1964, 18,290/64
8 Claims. (Cl. 42—54)

This invention relates to a toy gun intended to simulate the ejection of spent cases at each firing of an explosive cap.

The gun may be provided either with a repeating automatic firing system or with a single shot system if from time to time it is desired to fire one shot of a series of shots loaded in the gun. The toy gun may, for instance, be an imitation of a "tommy-gun" or other automatic gun.

It is an object of the present invention to provide an improved toy gun.

According to the present invention there is provided in a cap-firing toy gun, a cap-firing mechanism, and ejector mechanism for ejecting a spent cap from the gun substantially simultaneously with the action of the cap-firing mechanism.

The term, "ammunition," means herein a series of explosive caps connected to one another to form a unit which can be loaded into a toy gun. This unit may be a series of caps one following the other to form a preferably rectilinear strip or a unit of caps, differently formed, also annular or disc-shaped.

The detachment of a cap may occur at any instant, before, simultaneously or after the firing of each shot. Preferably however, the ejection of a spent cap is effected simultaneously with the firing of another cap. On the other hand, the ejection of a spent cap could also be effected at an instant different from its detachment, although it is preferable that the ejection should occur substantially simultaneously with the detachment of the cap.

An embodiment of a toy gun in accordance with the invention will now be described, by way of example, with reference to the accompanying diagrammatic drawings, in which:

FIG. 1 illustrates one embodiment of a toy gun in accordance with the invention, in a partly sectioned side view;

FIG. 2 illustrates a detail, to an enlarged scale, of FIG. 1 in the position prior to arming which is the same as that assumed subsequent to firing;

FIGS. 3 and 4 illustrate local transverse sections on the lines III—III and IV—IV respectively of FIG. 2;

FIGS. 5 and 6 are similar to FIG. 2 but illustrate two different positions of the members of the gun, namely 55 the position which the members assume at the end of the arming of a striking mass or hammer and the position after the firing stroke but before the return of the trigger to the position of FIG. 2;

FIG. 7 illustrates a longitudinal section on the line VII—VII of FIG. 2;

FIGS. 8 and 9 illustrate two local sections on the lines VIII—VIII and IX—IX of FIG. 2 respectively;

FIG. 10 illustrates a cross-section on the line X—X of FIG. 2;

FIG. 11 illustrates a local inclined section on the line XI—XI of FIG. 4;

FIG. 12 illustrates a cross-section on the line XII—XII of FIG. 11;

FIG. 13 is a perspective view of a strip of caps for the gun shown in the preceding figures;

2

FIG. 14 is an exploded perspective view of various parts of the gun;

FIGS. 15 to 20 illustrate details of the upper end of the magazine, in a perspective view, in a front view and in sections on the lines XVII—XVII, XVIII—XVIII, XIX—XIX and XX—XX of FIG. 16 respectively; and

FIG. 21 illustrates a view similar to FIG. 1 of a modification of the embodiment of the previous figures.

Referring now to the drawings, the casing 1 of a toy gun is formed from two substantially symmetrical portions of a thermoplastic synthetic-resin material, cavities and seatings for various members being provided therein. The stock 1a, a trigger guard 1b and a fore-sight 1c all form parts of the casing 1.

The stock 1a is formed with a housing for a magazine 3, which extends in a direction substantially normal to the sight line of the gun and the housing is formed with a lower end extension 3a to facilitate the loading and unloading operation. The magazine 3 is formed to receive slidably in a longitudinal channel member 3b fitted

therein, a strip of caps 5, which are brought individually into the firing position. The caps 5 are joined to each other by connection stalks 6 which project laterally and which are shaped to form a series of teeth each having

25 a stop or shoulder 6a directed downwardly and an upwardly facing inclined rear face 6b. The ammunition formed by the strip of members 5, 6 may be moulded in a single piece of thermoplastic synthetic-resin material, the caps 5 being loaded with an explosive charge. Alternatively, the caps can be made separately from one another and interconnected by a strip of card, cardboard or other material capable of being sheared in the same manner as the connections or stalks 6 of the strip shown

30 in the drawings and in particular in FIG. 13. The ammunition for the magazine may also be formed of several strip portions capable of being connected to one another. For this purpose, an extension 6c is provided with a pair of pins for engagement in a corresponding pair of holes formed in an opposite extension 6d of another similar strip. An extension 6e at the end having

35 the extension 6c serves to keep the last cap of the series in the right position, before also being expelled by shearing mechanism of the gun.

At the upper end the magazine 3 (see also FIGS. 15 to 20), has a stepped recess 3d which faces towards the barrel. Furthermore, one of the sides of the magazine is provided with an extension 3e and a longitudinal slot 3f; the opposite side, 3g terminates below the extension 3e to form a lateral opening, for hereinafter described purposes, in alignment with a lateral window 8 (see FIG. 4), in one of the parts of the casing 1. Spent caps can be ejected through this window 8. As shown in FIGS. 17

40 to 19, the channel 3b is provided with a portion of reduced cross-section 3h in which the lateral projection formed on the stalks 6 of the ammunition strip can engage for retention purposes.

The gun barrel 10 is slidable in a bore in the casing 1 and is at least partly uncovered over a central portion and is guided in a front portion of the casing 1 in alignment with the sight 1c, adjacent which an annular slide-way is formed for the barrel. The barrel is also extended in alignment with the stepped recess 3d of the upper section of the magazine 3. The barrel 10 can slide in the axial direction, the stroke being limited by a tooth 10a on the barrel which engages against two stops 1h formed in the casing 1. The barrel has a longitudinal bore and at the inner end this has a rectangular cross-section. A sheet metal member 12 is secured across the end of the bore of the barrel 10 and has an outwardly inclined flange 12a defining an aperture 12b. The flange 12a is substantially frusto-conical, is rearwardly directed and the

aperture 12b leads to the upper end of the magazine 3. One of the caps 5x which is in the firing position (FIGS. 2 and 4), must be coaxial with the aperture 12b and to this end is centered by the rim of said aperture when the barrel is suddenly moved in the firing stroke in the direction of an arrow f_2 (FIGS. 1 and 2). The cap 5x is located at the end of the bottom wall of the channel member 3b.

In the barrel 10 (see particularly FIG. 9), a pair of longitudinal grooves 13 (see FIGS. 9, 11, 14), is arranged to receive a plate 14 engaging the bottom of the grooves with its edges, and which is retained therein by the member 12 engaged in the square section portion of the bore of the barrel. The plate 14 carries a cylindrical member 14a which acts as the firing or striking pin. The member 14a is so arranged that when projecting centrally through the aperture 12b it can strike the explosive charge of the cap 5x and is aligned with the aperture 12b. The plate 14 has a shaped outer projection 14b, which extends from a track 12c in the sheet metal member 12. The projection 14b is chamfered at an edge 14c thus forming a cutting edge. This cutting edge 14c is arranged to contact one of the stalks 6 between the cap 5x which is in the firing position and a spent cap 5y immediately above it (chain lines in FIG. 4), which is located on the same level as the window 8. The plate 14 is inclined as shown in FIG. 4 so that the cutting edge 14c faces the window 8.

The barrel 10 has a projection 10c adjacent its inner end, against which a leaf spring 16 acts which is fixed in a seating 11 (FIG. 1), formed in the casing 1. The leaf spring 16 is so loaded that it biases the barrel 10 to move in the direction of the arrow f_2 . The firing pin 14a is thus urged towards the cavity of the cap 5x, which is in the firing position and is supported on the rear wall of the magazine 3.

When the barrel 10 has been moved in the direction of the arrow f_1 from the position shown in FIG. 1 to the position shown in FIG. 5 (thus additionally loading the spring 16), and is released from said position, the spring 16 causes a rapid stroke in the direction of the arrow f_2 . At the end of this stroke the firing pin 14a causes the firing of the explosive charge of the cap 5x and the severance of the stalk between the cap 5x and the cap 5y by means of the cutting edge 14c. The stalk is thus neatly sheared and the inclined profile of the edge 14c (FIG. 12), causes the ejection of the last cap 5y of the strip in the direction substantially of an arrow f_4 of FIGS. 4 and 12 through the window 8. Thus the severance and ejection of a cap is effected at each rearward movement of the striking mass formed by the barrel 10. Obviously the cutting edge 14c will reach the surface which provides the resistance necessary to effect the cutting and this surface is defined by a portion 1f of the casing 1 at the upper end of the magazine 3. The firing pin 14a is slightly shorter so as to allow the completion of a cutting stroke of the projection 14b but has a sufficient length to ensure the striking and thus the ignition of the explosive charge in the cap 5x. The projection 10a of the barrel 10 may also act as a limiting abutment for the firing stroke of the barrel 10 in the direction of the arrow f_2 , as well as acting as a limit to the stroke of the barrel 10 in the direction of the arrow f_1 .

The explosion gases can escape freely through the bore of the barrel 10 and through the aperture 12b of the member 12. When the barrel 10 has reached the cutting position, that is the position at the end of the firing stroke in the direction of the arrow f_2 , the edge of the aperture 12b will graze the outer edge of one of the caps 5 and will thus ensure the centering of the cap ready for firing and will support this edge so as to withstand better the pressure stresses caused by firing. Furthermore, the edge of the aperture 12b, in co-operation with the cap edge, prevents the back flow of gas from the outside of the cap, thus forming a labyrinth and an obstruction to the escape of the gas. However, the gas finds a free escape path

through the aperture 12b and the barrel and does not emerge in any substantial quantity from the side of the magazine.

In the last part of the firing stroke of the barrel 10, the pin 14a has already penetrated into the cavity of the cap 5x which is to be fixed and thus exerts a retaining action on the cap and of the strip of caps in the magazine 3. This arrangement is exploited with a device hereinafter described for effecting the return motion of means for advancing the strip of caps in the magazine. When the striking mass formed by the barrel 10 has been moved in the direction of the arrow f_1 to effect the arming stroke to the position shown in FIG. 5, the projection 14a and the cutting edge 14b are separated from the strip of caps 15 and this is free to be moved to advance the same strip by a pitch length and to locate a new cap in the firing position. The guide formed by the narrow portion 3h of the channel 3b exerts a retaining action on the ammunition in the upper zone of the magazine.

The barrel 10 is advanced in the firing stroke by the action of a trigger in the case of a single-shot gun, or by another device with an automatic gun, such as a tommy gun or a machine gun.

In the case of a single-shot gun, as illustrated, the trigger 19 lies within the trigger guard 1b. The trigger 19 also extends into the interior of the casing 1 in a recess formed below the rear portion of the barrel 10. The upper end of the trigger has a portion 19a of increased thickness which ends in a tooth 19b. The trigger 30 also has two lateral circular bosses 19c, and a pin 19d extends from each boss. The two pins engage in two slots 20 (see FIG. 10), formed in the opposed sides of the housing for the trigger 19, formed by the casing 1 and inclined to the centre line of the barrel 10. The trigger 35 19 is therefore free to move about the pins 19d and can be moved within the limits defined by the slots 20. A spring 21 housed in a bore 21b formed in the casing 1 acts on the upper portion 19a. The angle of inclination of the line of action of the force exerted by the spring 21 with respect to the direction of sliding of the barrel 10 is smaller than the angle of inclination of the slots 20. The inclination of the slots 20 and of the line of action of the spring 21, together with the size of the trigger 19 are such as to satisfy the hereinafter described purposes, in co-operation with the barrel 10. The barrel 10 has a 40 stop 10g which co-operates with the tooth 19a of the trigger 19. A cam profile 10h on the barrel 10 is formed forwardly of the stop 10g and co-operates with the tooth 19b.

In the position illustrated in FIG. 2, the tooth 19b is in engagement with the stop 10g and the pins 19d of the trigger are at the upper end of their stroke in the slots 20 and towards the rear end of the barrel 10. By acting on the trigger 19 in the direction of an arrow f_5 clockwise rotation of the trigger is effected and the thrust of the tooth 19b on the stop 10g causes an advance in the direction of the arrow f_1 of the barrel 10 and an additional loading of the spring 16 and compression of the spring 21. The position is thus changed from that shown in FIG. 2 to that of FIG. 5. The tooth 19b disengages 45 from the stop 10g leaving the barrel free to make the firing stroke under the action of the spring 16. During this stroke, the tooth 19b is in contact with the cam profile 10h. On releasing the trigger the spring 21 forces the tooth 19b to follow the cam profile 10h in the direction of the arrow f_2 and by reaction slides the pins 19d 50 along the slots 20 from the position of FIG. 5 to the position of FIG. 6 until the tooth 19b reaches the edge of the stop 10g again. At this point, the action of the spring 21 effects an upward movement of the trigger so that the tooth 19b enters the recess adjacent the stop 10g, and the pins 19d return to slide in the reverse direction along the slots 20 and pass from the 55 position of FIG. 6 back again to the position of FIG. 2.

Therefore, the device, formed by the trigger 19 loaded 70 by a small spring 21, effects the direct action on the strik-

ing mass and the return to the initial conditions of the device which serves for the arming and firing of the striking mass. When a repeating device is provided, the trigger may directly act on the striking mass, or on a lever equivalent to the trigger described.

On a side of the casing, within the same cavity provided for the trigger action, there is mounted a small lever 22, formed by a plate which is capable of pivotal motion in a plane parallel to that containing the axis of the barrel 10 and the vertical axis of the magazine 3. The lever 22 has an aperture with a projecting flange 22a (FIG. 7), on which the lever 22 is pivoted on the casing 1 intermediate its length. In order to engage the lever 22 to cause its pivotal movement, there is provided on one side of the casing 1, a hollow tubular projection 23 and on the other side of the casing 1, a projection 24 with a pin 24a engaging in the aperture 22a. By the action of joining the two portions of the casing 1, the lever 22 is mounted on the axis defined by the projections 23, 24 and can pivot about this axis. The lever 22 has a lug 22b forming a stop and a second lug 22c having an inclined cam profile, the stop and inclined profile being disposed on different sides of the pivot axis. The end of the lever 22 carrying the lug 22b is bent to form a tooth 22d with a thrust profile directed upward and an inclined profile directed downwards (see FIG. 4). The tooth 22d extends into the slot 3f of the magazine 3 and is arranged to engage the stops 6a of the strip of caps in the magazine, so as to move the strip upwardly, while the inclined back co-operates with the inclined profile 6b to override below a stop 6a, when the end of the lever 22 is moved downwardly. The lever 22 is resiliently flexible so that it can be displaced out of the pivot plane as in indicated in chain lines in FIG. 7, to facilitate this overriding.

The barrel 10 is provided with a projection 10i (FIG. 14), which lies between the lugs 22b and 22c. In the positions shown in FIGS. 2 and 6, the projection 10i is acting on the lug 22b, causing counterclockwise rotation of the lever 22 and thus the depression of the tooth 22d below a stop 6a corresponding to the cap beneath the cap 5x. When the barrel 10 is moved in the direction of the arrow f_1 to effect arming, the projection 10i contacts the inclined profile of the lug 22c causing clockwise rotation of the lever 22 and thus raising the tooth 22d. The advance of the strip 5, 6 to locate the spent cap in the upper position 5y and to locate a new cap in the firing position 5x is thus effected. The position of the strip of caps is determined by the profile of the lug 22c co-operating with the projection 10i. When the barrel is freed or released by the tooth 19b and the firing stroke takes place in the direction of the arrow f_2 , the projection 10i moves out of contact with the extension 22c. Towards the end of the firing stroke, after the pin 14a has entered the cavity of the cap in the line of firing thereby retaining the strip against spontaneous movement, the projection 10i strikes the lug 22b thus moving the lever 22 from the position of FIG. 5 to the position of FIG. 6. The tooth 22d is thus again depressed and passes to a subsequent stop 6a of the strip, being deflected during this stroke in a resilient manner in its own plane of pivoting thereby to return under the stop 6a of a new cap which is to be located in the firing position.

According to a further modification to be described hereinafter, the depression of the lever 22 is effected by the trigger on the return stroke effected by the spring 21.

According to a modification shown in FIG. 21, the gun is made with the barrel 101 forming part of the mouldings of the casing 100. Therefore, a slidible portion, forming the striking mass, is not visible from the exterior. While the same reference numerals are used for members similar to those of the previous embodiment, only those members are described hereinafter which differ from the corresponding ones of the previous embodiment. The striking mass is indicated by 110 and has the form of an inner section of the barrel 10 and

has an axial bore having an external surface carrying the parts 10c, 10g, 10h. The mass 110, furthermore, carries at the rear end the member 12 engaging the plate 14 as in the previous embodiment and the leaf spring 16 acts on the striking mass as in the first embodiment. At the front end, the striking mass 110 has a tubular relatively thin-walled member 110a, which is inserted in a bore 101d, extending through the front portion of the casing 100 to the barrel 101. Consequently the explosion gases are discharged, as in the previous embodiment through an axial bore corresponding to the barrel of an actual gun. In FIG. 21, a projection 122b on the lever is acted upon by the trigger when the trigger passes from the position corresponding to that of FIG. 6 to the position corresponding to that of FIG. 2. The lug 22b is eliminated and the stiffness of the spring 21 will be made sufficient to accomplish this additional action.

Other aspects of the illustrated embodiment are described and claimed in co-pending patent application Serial No. 479,112 filed Aug. 12, 1965, under the title, "Toy-Gun Ammunition."

The drawings illustrate only as practical demonstrations of the invention, said invention being capable of modification without however departing from the scope of the appended claims. In particular, the invention may be applied to a gun with a repeating percussion system (tommy gun or machine gun) in which the trigger 19 is replaced by a mechanised control having a certain operational range and a certain control rate.

Furthermore, the mechanism for severing the caps may be arranged merely to detach the spent caps from the strip instead of severing the caps together with a part of the connecting stalk.

We claim:

1. In a cap-firing toy firearm for use with caps arranged in strip form, cap-firing means, and severing and ejector means operable substantially simultaneously with the cap-firing means whereby to sever a spent cap from the strip of interconnected caps and eject said spent cap from the firearm while an adjacent cap is being fired.
2. In a cap-firing toy gun for use with interconnected caps, a cap-firing mechanism, severing and ejector means operable simultaneously with the cap-firing mechanism to sever a spent one of the interconnected caps and to eject said spent cap from the gun while an adjacent cap is being fired, and advancing means operable whenever the gun is fired to advance the interconnected caps by one cap past the cap-firing mechanism.
3. In a cap-firing toy gun for use with interconnected caps, a cap-firing mechanism, severing and ejector means operable simultaneously with the cap-firing mechanism to sever a spent one of the interconnected caps and to eject said spent cap from the gun while an adjacent cap is being fired, said severing means comprising, a blade having a cutting edge, an adjacent face of which is inclined to the longitudinal direction of the interconnected caps whereby the said inclined face by acting on the spent cap causes the ejection of the said spent cap from the gun in a desired direction, and advancing means operable whenever the gun is fired to advance the interconnected caps by one cap past the cap-firing mechanism.
4. In a toy gun according to claim 3, a striking mass movable with respect to the interconnected caps, said mass carrying at least a part of the cap-firing mechanism and the severing and ejector means,

whereby the movement of the mass towards one of the caps at a firing position causes the firing of said one cap by means of the firing mechanism and severance and ejection of a spent cap of the interconnected caps, and whereby movement of the mass away from the caps causing the indexing of the cap next adjacent the said one cap into the firing position by the said advancing means.

5. In a toy gun according to claim 4,

a barrel,
said barrel forming at least a part of the said striking mass.

6. In a cap-firing toy gun for use with caps arranged in strip form,

a cap-firing mechanism,
severing and ejector means operable substantially simultaneously with the cap-firing mechanism to sever a spent cap from the strip and eject said cap from the gun while an adjacent cap is being fired, and guide means for guiding the strip through the gun and past a firing position, the guide means having an opening therein through which the spent caps are ejected after severing.

7. In a cap-firing toy gun for use with caps arranged in strip form,

a cap-firing mechanism,
a firing-pin forming part of the cap-firing mechanism,
a striking mass carrying the firing pin, and
an end member on the said striking mass, said end member having an aperture through which the firing pin protrudes and which has a periphery such that

10

15

20

25

30

it engages a cap of the strip to align the cap accurately in the firing position when the striking mass is making a firing movement.

8. A toy gun for use with a strip of caps interconnected by elongate stalks disposed laterally of the caps and having a tooth on each said stalk, said gun comprising,

a casing,
a barrel, movable longitudinally with respect to the casing,

a housing forming part of the casing and arranged to carry a strip of caps,

a cap-firing mechanism operable to fire a cap disposed at a firing position,

an advancing mechanism operable by movement of the barrel to index the strip of caps to bring successive caps to the firing position,

a severing mechanism operable by movement of the barrel to sever and eject from the gun a spent cap, and a trigger operable to operate the cap-firing mechanism.
